UNITED STATES PATENT OFFICE

JOSEPH H. JACOBS, OF ROCHESTER, NEW YORK

CURLING-IRON ATTACHMENT

Application filed April 1, 1929. Serial No. 351,539.

This invention relates to improvements in curling iron attachments of the type disclosed and claimed in U. S. Letters Patent 1,691,115, granted to me on November 13, 1928.

5 In the employment of curling irons especially of the type that is heated electrically, it often happens that if the operator fails to exercise great care the heated portion of the iron will come in contact with the scalp 10 with the result that serious burns often take place.

In the patent above identified, I have disclosed and claimed a protector that can be applied to a curling iron of ordinary construction and which serves to protect the person whose hair is curled against injury.

15 It is the object of this invention to produce an improved construction of protector which can be employed in connection with curling irons having blunt recessed ends as distinguished from the sharp, conical ends of the curling irons illustrated in my patent.

It is another object of this invention to produce a protector having such shape that 20 it will not roll when laid upon a surface and which therefore serves as a support for the curling iron.

The above and other objects which may become apparent as the description proceeds 25 are attained by means of a construction and an arrangement of parts that will now be described in detail, and reference for this purpose will be had to the accompanying drawing, in which the invention has been illustrated, and in which:

Fig. 1 is a side elevation of a curling iron showing my improved protector in place thereon, a portion of the curling iron having been broken away to better disclose the construction; and

40 Fig. 2 is a perspective view of a portion of the protector.

In the drawing numeral 1 indicates the handle of a curling iron to which the cylindrical heating member 2 is attached. A clamping member 3 is pivoted at 4 to ring 5 and is acted upon by means of a spring 6 which tends to move it to clamping position and this spring is provided with an opening 50 for the reception of a pin 7, all in the usual

and well known way. The free end of the heating member, instead of being pointed as is ordinarily the case, is provided with a central recessed portion 8. My improved protector, consists of a bar 9 of some poor heat 55 conducting material, such as fiber, one end of this bar is provided with an opening to which a spring 10 is attached. The other end of this spring is attached to a ring 11 that encircles the heating member 2 and is 60 located between the ring 5 and the end of handle 1. The other end of the protector terminates in a conical point 12 that lies to one side and which has its rear surface provided with a conical point 13 that is adapted 65 to enter the recess 8 in the end of the heating member and to hold the protector in place. It will be seen that the protector can rotate with respect to the heating element 2 and that due to the action of the spring 10 and 70 the point 13, it is securely held in place. The outer surface of the protector is preferably 75 concave as indicated by numeral 14 in Fig. 2, so that when the curling iron is laid down on a flat surface, it will support the same in the position shown in Fig. 1. This is a great convenience for the operator as by this means the iron can be supported in any desired position when not in use.

The construction illustrated in this drawing has a considerable advantage over the one illustrated in my patent due to the fact that when the heating member of the curling iron has a conical end, the protector must have a recess into which this end projects 80 and this increases the size of the end portion of the protector which therefore becomes large and clumsy, and it also leaves a projecting edge that is liable to catch the hair and interfere with the operation. When the 85 heating member is provided with a recess in its end it is possible to make the end of the protector much smaller and to curve the same so as to conform to the curvature of the end of the heating member, thereby making the 90 curler neater in appearance and much more convenient in its operation.

Having described the invention what is claimed as new is:

1. A hair curler having an elongated heat- 100

ing element of good heat conducting material provided at one end with a handle and having a depression in its other end, a protector comprising an elongated member of poor heat conducting material extending along one side of said element, said protector having an offset portion near one end, said offset having a conical portion adapted to extend into the depression and a spring attached to the other end of the protector for exerting a pull thereon tending to hold the conical projection in the depression.

2. A protector for use with curling irons having an elongated heating element having one end provided with a handle and the other end provided with an axial depression, said protector consisting of an elongated member of poor heat conducting material having one end provided with a laterally extending lug having a pointed projection extending towards the other end, said projection being adapted to extend into the depression in the heating element, the protector having a substantially rectangular cross section.

25 In testimony whereof I affix my signature.
JOSEPH H. JACOBS.
